KARL ARNSTEIN, OF AKRON, OHIO, ASSIGNOR TO LUFTSCHIFFBAU ZEPPELIN GESELLSCHAFT MIT BESCHRANKTER HAFTUNG, OF FRIEDRICHSHAFEN, BODENSEE, GERMANY.

RIGID AIRSHIP.

Application filed January 16, 1925, Serial No. 2,832, and in Germany February 11, 1924.

My invention relates to rigid airships the hull of which is made up of longitudinal and of cross members and especially to the construction of such cross members.

- 5   The cross members of a rigid airship are usually polygonal ring trusses comprising circumferential girders and a wire bracing. The wire bracing besides stiffening the ring truss in itself against bending stresses serves 55
 10 for steadyng the end walls of the gas cells inserted between every two braced cross members, especially so in case of difference in pressure in two adjacent cells. Under such circumstances which will occur for example with the leakage of one cell, the surplus pressure in one direction will cause an inward tension on the circumferential girders of the ring truss. Such tension stress is one of the most difficult main stresses to be 60
 15 carried by the ring truss.

My invention does away with the possible occurrence of such dangerous stresses by totally omitting the wire bracing and by making the circumferential girders so strong 25 as to be practically stiff against bending stresses resulting from the ship's load. The end wall of a gas cell in case of leakage in the adjacent cell will bulge through the middle opening of the ring structure. For the 30 purpose of giving support to this wall, if thought necessary, a resilient or elastic network may be provided which transmits part of the stress to the circumferential truss. But as the net work will be chosen so as to 35 allow a considerable pitch of camber with regard to the ring plane the stresses transmitted will be practically negligible when compared with the stresses resulting from the former wire bracing where the pitch of 40 camber was very low and also an advance tension had to be given to the wires.

Having given a general description of my invention I now want to point out the details thereof referring to the drawing which 45 shows an example embodying my invention.

Fig. 1 is a cross section through the airship showing the ring truss in front elevation. Fig. 2 is the corresponding side elevation of a portion of the ship. In both figures the outer cover of the ship and the gas cells are assumed to be taken off.

The cross member A is a ring-shaped truss comprising outer truss members *a* and inner truss members *b* connected with each other by struts *c*. This ring truss is absolutely 55 stiff against bending stresses. A net or the like *d* may be provided which is fastened to the ring structure by ropes *e*, preferably connecting to the outer chords *a* of the structure, the ropes *e* approximately equalling in 60 length that of the struts *c*. I prefer to use strings of hemp or ramie for the network. This also has to be resilient if it is not made elastic. In Fig. 2 the position of the net is shown which it will take in case the gas cell 65 *f* fitting into the compartment at the left of ring truss A is deflated and the adjacent gas cell *g* at the right of the ring truss bulges through the middle opening of the ring.

I want it understood that I do not limit 70 myself to the example described or shown in the drawing as many variations will occur to persons skilled in the art.

What I claim is:

1. In the hull of a rigid airship a longitudinal member and a cross member, said cross member constituting a ring truss stiff against bending stresses in itself without cross bracing, and a network situated within and fastened to said ring truss and adapted 75 to bulge out of its plane.

2. In the hull of a rigid airship a longitudinal member and a cross member, said cross member constituting a ring truss stiff against bending stresses in itself without cross bracing, and an elastic network situated within 80 and fastened to said ring truss and adapted to bulge out of its plane.

3. The hull of a rigid airship comprising longitudinal members and cross members 85 constituting individual compartments adapted to have gas cells inserted, one of said cross members constituting a substantially annular truss in such dimensions as to be stiff against bending stresses resulting from 90 the ship's load without internal reinforcing bracing, and a network inserted within and fastened to said annular truss and adapted to bulge into one of the said compartments 95 adjacent to said cross member.

KARL ARNSTEIN.
